FRAME WITH SLIDABLE TOOL BIT

Richard Itaru Nakamura, Waipahu, Oahu, Territory of Hawaii, assignor to Yoshiko Nakamura, Waipahu, Oahu, Territory of Hawaii

Application January 9, 1947, Serial No. 721,048

4 Claims. (Cl. 7—15)

1

This invention relates to the broad class of can openers and has more particular reference to a multiple purpose kitchen and household implement which is characterized by can opening means and is provided with extra facilities usable in other capacities.

An object of the invention is to provide a simple, practical and efficient implement of a type embodying an open loop-like frame and an extensible, retractable and reversible tool or implement carried by said frame.

In carrying out the principles of the invention, I contemplate using an elongated substantially U-shaped frame formed from scrap metal, the outer free end portions of the limbs of said frame being especially designed to accommodate a multiple purposed implement which is slidably and detachably mounted in place.

Another object of the invention is to form a hook on the terminal of one of the free end portions or limbs of said frame which hook co-acts with the adjacent implement in providing an appropriate bottle cap remover.

A further object of the invention, structurally speaking, is to provide a simple implement in bar-like form, the same being rectilinearly straight, fashioned at one end with an offset pointed can punch and having the opposite end formed into a bit which may be used either as a screw-driver or for prying can lids loose for easy removal purposes.

Novelty is also predicated upon a handle forming frame having substantially parallel and closely spaced limb portions, these being mechanically connected through the medium of headed rivets and said rivets serving as guide and retention elements for the extensible and retractable multiple purposed implements.

Additional novelty is predicated upon a detachable U-shaped clip and a detent therefor, said clip serving to embrace co-acting limb portions and a portion of said implement to render the overall structure sufficiently strong and stable for reliable use.

Other objects, features and advantages of the invention will become more readily apparent from the following description and the accompanying illustrative drawings.

In the drawings, wherein like numerals are employed to designate like parts throughout the same:

Figure 1 is an elevational view, partly in section, of a so-called can opener constructed in accordance with the principles of the present invention;

Figure 2 is a view in elevation and at right angles to Figure 1;

Figure 3 is a view based on Figure 1 and showing the manner in which the extensible and retractable tool or implement is retracted into the

handle frame for compactness and convenience; and,

Figure 4 is an enlarged cross sectional view on the plane of the line 4—4 of Figure 2, looking in the direction of the arrows.

Referring now to the drawings by distinguishing reference numerals, it will be seen that the frame unit or means is denoted, generally speaking, by the numeral 6, the same being formed from strap metal and said strap being bent intermediate its ends and upon itself as at 7 into general U-shaped form. The limb portions are denoted by the numerals 8 and 9, the limb 8 being somewhat longer than the limb 9 and terminating in a hook 10 which serves, in a manner to be hereinafter described, as a bottle cap remover. The free end portion of the limb 9 is inwardly offset as at 11 to provide a rectilinearly straight portion 12. The limb 8 is inwardly offset by lateral bending as at 13 and is again bent laterally and inwardly as at 14 to provide a rectilinearly straight portion 15, this being disposed in close spaced parallelism to the limb portion 12. The outer ends of the portions 12 and 15 are provided with spaced rivets 16 which serve to assemble the parts and which also serve to accommodate the projectile, retractile and reversible tool 17. This part 17, in the main, is a rectilinearly straight bar which is rectangular in cross sectional form and which slides between the parts 12 and 15 of the limbs and which is, when in operation, held in place between the spaced rivets 16. One end of the tool is laterally offset and pointed as at 18 to provide a can punch. The opposite end is suitably tapered and formed as at 19 to provide a bit which may be used either as a screw-driver or as a lid prying and lifting element.

I provide a sleeve 20 which is slidable on the tool and said sleeve serves as a carrier for a cutting blade 21, said blade being lateral to the sleeve and being carried by an arm 22 which is mounted in the sleeve and which has one end hooked and clenched against the sleeve as at 23 for assembling and retention purposes. The sleeve and blade may be adjusted, as a unit, in relation to the can punch 18 in an obvious manner.

I next call attention to a U-clip 24 which is applicable and detachable as shown in dotted lines in Figure 3. This clip fits over the limb portions 12 and 15, as shown, and also embraces the edge portions of the tool to provide the desired stability in relationship of parts when set up for use. The bight portion of the clip is provided with a keeper notch 25 to accommodate the hooked end of a spring detent or latch 26.

The numeral 27 designates a cork-screw which is pivoted or otherwise secured to the limb 8 as indicated at 28. This is an optionally usable 60 feature.

It is obvious that the tool may be slid in or out, the same being shown projected to "an out" position in Figure 1, and being retracted to "an in" folded position in Figure 3. Not only is the tool retractable and projectible in relation to the frame 6, but it is also reversible. That is to say, the tool may be bodily slipped out from between the pins 16 and limb portions 12 and 15 and then turned through a half circle and reinserted for reversible use.

As before mentioned, the hook 10, when used in conjunction with the bar or tool 17 may be employed as a de-capper.

Comparing Figure 3 with Figure 1, it will be seen that the tool means 17 has been turned and fully reversed. That is to say, in Figure 1, we see the bar 17, the basic part of said tool means, projected with the bit 19 clipped and situated within the confines of the U-frame 6, the punch 18 and can cutting blade 21 having been extended for use, during which said punch is punched through and anchored in the can top and the blade is raked around the marginal edge and forced in and down to make the desired circular cut. Of course, said tool means can be shoved bodily up and into the frame when out of use (as shown in dotted lines) if and when the user desires to so retract and "store" it in a compact out-of-the-way position. In Figure 3 said tool means is pictured in full lines in a corresponding out-of-the-way position. However, it should be noted that in the latter figure, it has been reversed, and to do this, the user simply slips and withdraws said tool from the frame 6 (Figure 1) and then turns it upside down and inserts the bit end 19 between the limb-ends 12 and 15, angling said end 19 between the assembling and retaining studs or rivets 16, and then "backs" the punch-end 18 into the frame 6. During this changeover procedure, and to install said bit 19 for projection and use, the brace-clip 24 is unsnapped from its latch 26 and bodily detached, after which said clip is replaced.

In respect to structural features of the invention, the reader will note the closely spaced and inter-related limb-ends 12 and 15 and the provision of the studs 16 connecting said ends and readying same for insertion and retention of the tool means. Further, the provision of the clip 24, which is saddled in place and held by the snap-latch 26 is noteworthy, for said clip embraces both the limb-ends and tool-bar 17 and effects a non-twisting and stabilized association of elements. In fact, the studs 16 and limb-ends alone do not well serve to adequately assemble and retain the tool means 17. Hence, the need for said clip or some equivalent sustaining and strengthening means.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

What is claimed as new:

1. A structure of the class shown and described embodying an elongated substantially U-shaped

frame embodying spaced parallel limb portions, said limb portions being substantially rectangular in cross-section, a resilient clip positioning and retaining latch disposed against the free end portion of one of said limbs, a pair of studs piercing a portion of said latch and adjacent portions of said limbs and securing the latch in place and the limbs together, said studs being disposed in spaced parallelism, a tool bar lodged but slidable between said limbs and slidable between the studs, and a U-shaped clip removably fitted over one limb and having its end portions straddling both limbs to assist in maintaining the tool bar against displacement, said latch being releasably connected with said clip.

2. A device of the class shown and described, comprising a U-shaped frame having limbs disposed in closely spaced parallelism, the free end portions of its limbs inter-connected by a pair of complementary, spaced studs parallel to each other, a tool bar slidable in and out of said frame and between said limbs and studs, and a relatively small keeper clip detachably mounted on said limbs adjacent to said studs, said clip embodying means embracing said limbs and serving to assist in holding the tool bar from displacement laterally of said limbs.

3. A convertible and multiple purpose implement of the type shown and described comprising an elongated U-shaped frame having outer ends of its limb portions disposed in closely spaced parallelism, a pair of studs rigidly mounted in the terminal ends of said limb portions, said studs being at right angles to the longitudinal axis of the frame and substantially parallel to each other, said limb portions being rectangular in cross-section, a tool bar also rectangular in cross-section fitted slidably between said limb portions and also between said studs, and a U-shaped keeper clip fitted removably over said limb portions inwardly of said studs and adapted to assist in guiding and retaining said tool bar.

4. A convertible and multiple purpose implement of the type shown and described comprising an elongated U-shaped frame having outer ends of its limb portions disposed in closely spaced parallelism, a pair of studs rigidly mounted in the terminal ends of said limb portions, said studs being at right angles to the longitudinal axis of the frame and substantially parallel to each other, said limb portions being rectangular in cross-section, a tool bar also rectangular in cross-section fitted slidably between said limb portions and also between said studs, a U-shaped keeper clip fitted removably over said limb portions inwardly of said studs, and a resilient retaining latch secured to said limb portions by way of said studs and releasably engaging said clip.
